UNITED STATES PATENT OFFICE.

WALTER FERRIS, OF SOUTH MILWAUKEE, WISCONSIN, AND LOUIS WEHNER, OF EVANSVILLE, INDIANA, ASSIGNEES TO BUCYRUS COMPANY, OF SOUTH MILWAUKEE, WISCONSIN, A CORPORATION OF WISCONSIN.

DUMPING MECHANISM FOR DRAG-LINE EXCAVATORS.

1,099,642.

Specification of Letters Patent.

Patented June 9, 1914.

Application filed May 13, 1912. Serial No. 696,807.

To all whom it may concern:

Be it known that we, WALTER FERRIS, a citizen of the United States, residing at South Milwaukee, in the county of Milwaukee and State of Wisconsin, and LOUIS WEHNER, a citizen of the United States, residing at Evansville, in the county of Vanderburg and State of Indiana, have invented a certain new and useful Improvement 10 in Dumping Mechanism for Drag-Line Excavators, of which the following is a specification.

Our invention relates to improvements in dumping mechanism for drag line excavators 15 and is illustrated in the accompanying drawings, wherein—

Figure 1 is an elevation showing the bucket in the excavating position; Fig. 2 a similar elevation showing the bucket in the 20 hoisting position; Fig. 3 a plan view of the dumping mechanism; Fig. 4 a similar plan view of Fig. 3 in a modified form.

Like parts are indicated by the same letter in all the figures.

The excavator boom or derrick A, which is supported from an excavating carriage or car not shown, carries the return sheave A¹ and the dumping drum A². The bucket A³ is provided with the bail A⁴ pivotally attached thereto and supported by the sheave A⁵ and is provided with the handle A⁶. The dumping rope A⁷ is attached to the handle A⁶ and is wound about the drum A², being fastened thereto at its inner end as indicated. The hoisting rope A⁸ is wound about the drum A² in the opposite direction from the rope A⁷ and has one end fastened thereto. The arrangement of the two ropes is such that as the drum rotates, one is paid off and the other wound upon the drum and vice versa. The rope A⁸ passes over the drum A² down over the sheave A⁵ up over the sheave A¹ and thence to the hoisting engine not shown. The drum A² is provided with the brake drum B rigidly attached thereto. The brake band B¹ is rigidly attached at one end to the boom A, passes around the brake drum B and is pivotally attached at its other end to the bell crank lever B² which is pivotally mounted on the boom A. The controlling link connection B³ may be actuated by the operator from the controlling platform not shown to rock the bell crank lever B², thus tightening the belt or band B¹ around the

brake drum B. The spring B⁴ connected at one end to the link B⁵ pivoted to the bell crank lever B², and at the other end to the link B⁶ pivoted on the boom is adapted yieldingly to hold the bell crank in the inoperative position, thus permitting the drum to rotate normally free from interference.

In the modified form indicated in Fig. 4, the drum C, having the dividing flange C¹, is substituted for the drum A². In this form the flange C¹ separates the ropes A⁷ A⁸ where they are wound upon the drum and prevents their coming in contact one with the other.

It will be evident that while we have shown in our drawings an operative device, still many changes might be made in the size, shape and arrangement of the parts without departing materially from the spirit of our invention and we wish, therefore, that our drawings be considered as diagrammatic.

The use and operation of our invention are as follows:—When the bucket is to be used for excavating, it is thrown out and dropped upon the ground in such manner that the cutting edge is in contact with the material to be excavated. The hoisting rope is then drawn in and the bucket is drawn forward by means of the handle. The angularity of this handle is such that the bucket will penetrate the soil and fill itself. When the bucket is filled, the excavating rope is loosened and the hoisting mechanism is put into operation to lift the bucket. The pivotal point of the hoisting bail is so disposed with respect to the weight of the bucket and contents that the bucket when hoisted assumes the position indicated in Fig. 2. The drawing in of the hoisting rope lifts the rear-most end of the bucket by means of the bail. This causes the center of gravity of the load to shift toward the pivotal point of bail, making the pull on hoisting rope A⁸ enough greater than the pull on dumping rope A⁷ to cause the rope A⁸ to unwind from the dumping drum, thus causing the dumping rope A⁷ to wind upon the drum and thereby lift the bucket to the desired height without further tilting. When the bucket is to be dumped, the brake on the dumping drum is tightened and the rotation of this drum is stopped. There is then no tendency for the handle end of the bucket to rise. As the hoisting mechanism continues this move-

ment, the rear end of the bucket is lifted until it is tilted into such a position that the contents are dropped out of the bucket. In case sticky materials have been excavated and the bucket will not free itself by gravity, the hoisting mechanism is operated to lift it up to a considerable height. It is then dropped through a few feet, jerking the material out, the strain of the stopping of the descent being carried partly by the braking mechanism on the dumping drum and partly by the braking mechanism at the other end of the cable on the hoisting machinery not shown.

In the modified form the lengths of cable as they are hauled in or paid out from the dumping drum, are separated by the flange which prevents any possibility of their tangling or wrapping one around the other and prevent any undue wear or other difficulty.

We claim:

In a drag line excavator a combined hoisting and dumping rope made up of two separate consecutive portions, one of them a

dumping portion, the other a hoisting portion, wound around a drum in opposite directions and fastened rigidly thereto at their ends, a bucket, the free end of the dumping portion being fastened thereto, a sheave on the bucket about which the hoisting portion travels and means for drawing in the free end of the hoisting portion to unwind the hoisting portion from the drum and wind the dumping portion upon the drum to raise the bucket, and means for holding the drum against rotation without interrupting the movement of the hoisting portion about the sheave to dump the bucket.
